UNITED STATES PATENT OFFICE.

HILDA KAJI, OF PHILADELPHIA, PENNSYLVANIA, ASSIGNOR TO MORRIS B. LEVENTHAL, OF PHILADELPHIA, PENNSYLVANIA.

DESIGN FOR A TEXTILE FABRIC OR SIMILAR ARTICLE.

Application filed November 18, 1921. Serial No. 516,210. Term of patent 7 years.

To all whom it may concern:

Be it known that I, HILDA KAJI, a citizen of the United States, and a resident of the city of Philadelphia, county of Philadelphia, State of Pennsylvania, have invented a new, original, and ornamental Design for Textile Fabrics or Similar Articles, of which the following is a specification, reference being had to the accompanying drawing, forming part thereof.

The said drawing illustrates the design which is repeated indefinitely on the goods.

I claim:

The ornamental design for a textile fabric or similar article, substantially as shown.

In testimony whereof I have hereunto signed my name this 7th day of November, A. D. 1921.

HILDA KAJI.
